HEATING OF FLUIDS

Lev A. Mekler, Chicago, Ill., assignor to Universal Oil Products Company, Chicago, Ill., a corporation of Delaware

Application July 8, 1935, Serial No. 30,222

3 Claims. (Cl. 122—356)

This invention particularly refers to an improved process and apparatus for improving the distribution of heat in furnaces of the type wherein a major portion of the heat imparted to 5 one portion of the fluid conduit is supplied by radiation from the materials undergoing combustion and the hot refractory walls of the furnace while the major component of the heat imparted to another portion of the fluid conduit is 10 supplied by convection, i. e. direct contact between the fluid conduit and the hot combustion products.

Furnaces of the general type above referred to are commonly termed "radiant and convection furnaces" and this general method of heating is now commonly employed in most modern furnaces for the continuous heating of fluids including steam boilers as well as oil conversion and distillation furnaces. The advantages of this 20 type of furnace are too well known to require discussion here. One of its chief disadvantages commonly encountered, however, results from the excessive and uncontrolled superimposing of radiant and convection heat at some point in the 25 fluid conduit which, in most cases, is adjacent a point in the furnace where the general direction of flow of the hot combustion gases or the materials undergoing combustion is changed. The high rates of heating at this point in the 30 fluid conduit, resulting from the absorption of heat transmitted by radiation from the materials undergoing combustion and the hot refractories as well as heat transmitted by washing of the 35 fluid conduit with high temperature combustion gases, is particularly detrimental in cracking operations wherein excessive localized heating usually results in the formation and deposition of coke in the fluid conduit which limits both the 40 efficiency of the furnace and the length of time which it can be operated without shutting down for cleaning.

The primary purpose of the present invention is to improve the distribution of heat to various 45 portions of the fluid conduit in furnaces of the general character above mentioned and more particularly to decrease the rate of heating at one or more points in this fluid conduit wherein heat absorbing surfaces which are exposed to fairly high rates of heating by radiation are also subjected to excessive additional heating by convection resulting from washing of the surfaces with 50 hot combustion gases. This is accomplished by the introduction of controlled amounts of steam into the stream of combustion gases at a suitable 55 point in their path of flow ahead of their point

of contact with the fluid conduit. This not only serves to partially blanket that portion of the fluid conduit washed by the combustion gases but, since steam has a high specific heat, it will act as a carrier, absorbing heat in that portion of the furnace adjacent its point of introduction and imparting it to the fluid conduit in a zone farther along the path of flow of the combustion gases wherein heating by convection predominates. Preferably saturated or exhaust steam is employed for the purpose of the present invention since more heat will, of course, be absorbed by low temperature steam than by superheated steam or, when desired, it may be supplied to the furnace in the form of water or water-vapor. Normally, however, the temperature of the furnace and the quantity of water employed is such that it will be in the form of steam by the time it is commingled with the combustion 10 gases.

Figure 1 of the accompanying diagrammatic drawings illustrates one specific form of furnace in which the features of the present invention may be utilized to advantage. It will, however, be understood that the invention is not limited to use in this or in any other specific form of structure since it is applicable to any heater wherein heat absorbing surfaces exposed to radiation are also subjected to heating by the wash 20 of hot combustion gases.

Figure 2 of the drawings illustrates one specific flow arrangement for the oil in the same furnace shown in Figure 1, and Figure 3 is illustrative of the type of heating curves obtained with and without employing the features of the present invention in a furnace of the type shown in Figures 1 and 2.

Referring to the drawings, the main furnace structure comprises end walls 1 and 2, a roof 3, a floor 4 and side walls not shown in the particular view of the furnace here illustrated. The interior of the furnace is divided by means of bridge wall 5 into two zones comprising combustion and heating zone 6 and fluid heating zone 1.

In the particular case here illustrated two parallel rows of horizontal tubes 8 are located adjacent the roof 3 of the furnace and receive heat at a relatively high rate by radiation from the materials undergoing combustion in combustion and heating zone 6 and the hot refractory walls 50 of the furnace. Another tube bank comprising a plurality of rows of horizontally disposed tubes 9 is located within fluid heating zone 7 and this portion of the fluid conduit receives fluid heat predominantly by contact with the hot combus- 55

tion gases from combustion and heating zone 6. The upper two or three rows of tubes in fluid heating zone 7 are also, in many cases, subjected to appreciable heating by radiation from the 5 combustion gases as well as from the adjacent hot refractory furnace walls.

Regulated quantities of combustible fuel and air are supplied to combustion and heating zone 6 by means of suitable burners such as indicated, 10 for example, at 10 and combustion occurs in zone 6 of the furnace. The ratio of air to fuel is preferably so regulated that combustion is substantially completed before the combustion products leave zone 6 of the furnace and the resulting 15 hot combustion gases pass over bridge wall 5 and are directed downward through fluid heating zone 7 to flue 11 from which they may pass to a suitable stack, not illustrated.

It has been found in furnaces of the form here 20 illustrated, which are employed extensively for the conversion of hydrocarbon oils, that when coking difficulties are encountered the greatest amount of coke is found in that portion of the tube bank adjacent the roof which is located 25 above bridge wall 5 (the approximate location of this zone being indicated in the drawings at 12) and in some cases in the upper two or three rows of the fluid conduit in fluid heating zone 7. This is attributed to the fact that these particular 30 zones, while subjected to relatively high rates of heating by radiation are also washed by the hot combustion gases and, therefore, subjected to appreciable and uncontrolled amounts of additional heating by convection. In this form of 35 furnace therefore the present invention consists in providing for the introduction of steam into the combustion gases ahead of their point of contact with the tubes in zone 12 and/or, when desired, above fluid heating zone 7. This may 40 be accomplished by the use of suitable headers or spray lines indicated at 13 and 14 to which water, water vapor or steam may be supplied and from which it may be introduced into the stream 45 of combustion gases. The steam thus introduced serves to partially blanket the tubes of bank 12 and/or the upper two or three rows of tubes in fluid heating zone 7 to protect the same from excessive heating and the heat absorbed by the steam is imparted to the tubes of the fluid 50 conduit within fluid heating zone 7 farther along the path of flow of the combustion gases, thereby securing better distribution of heat to the various portions of the fluid conduit and preventing excessive rates of heating in zone 12 and/or, when 55 desired, in the upper rows of tubes in fluid heating zone 7.

It will be understood that the invention is not limited to any particular flow arrangement through the fluid conduit of the furnace illustrated or to any particular sequence between the various portions of the fluid conduit. Preferably, however, the fluid undergoing heating passes in series through adjacent tubes in each 60 section of the fluid conduit and the two sections 65 are connected in series.

As a specific example of the operation and advantages of the present invention as applied to a furnace of the type above illustrated and described, employed for the conversion of hydrocarbon oil, the path of flow of the oil through the fluid conduit is indicated in Figure 2. The reference numbers in Figure 2 indicate portions of the furnace indicated by the same reference numbers in Figure 1. The charging stock is 70 heated to an outlet conversion temperature of 75

approximately 910° F. The type of heating curve obtained without employing the features of the present invention is indicated in Figure 3 of the drawings as curve "A". It will be noted that in that portion of the fluid conduit corresponding 5 to zone 12 and to the upper rows of tubes in fluid heating zone 7 the rate of temperature rise is appreciably increased. In this operation the temperature of the combustion gases indicated by thermocouples located adjacent zone 12 of the 10 fluid conduit approximates 1500-1550° F. while the combustion gas temperature measured by thermocouples located above fluid heating zone 7 approximate 1350° F. and the temperature of the gases leaving the fluid heating zone was approxi- 15 mately 975° F. This operation was terminated after a run of approximately ten days, due to hot tubes in zone 12 of the fluid conduit and a layer of hard coke approximately one-half inch thick 20 was found in the tubes of this section. By introducing controlled quantities of exhaust steam into the stream of hot combustion gases at approximately the points indicated by headers 13 and 14 in Figure 1 of the drawings the temperature of the combustion gases adjacent zone 12 is 25 reduced to approximately 1450° F. The type of heating curve obtained during this operation is indicated as curve "B" in Figure 3 of the drawings. The plant was operated continuously for a period of 22 days. At the end of this period 30 the coke deposited in the tubes of section 12 of the fluid conduit averaged approximately one-sixteenth inch in thickness. The capacity of the cracking unit was also increased from approximately 1500 barrels per day to 1650 barrels per 35 day by employing the features of the present invention.

I claim as my invention:

1. In a process for the heating of fluids while passing the same in a continuous stream through 40 a fluid conduit wherein a portion of the fluid conduit is subjected to relatively high rates of heating by radiation from combustion gases and hot refractory furnace walls, another portion of the fluid conduit is subjected to excessively high 45 rates of heating by radiation and by direct contact with said combustion gases and another separate portion of the fluid conduit subjected to lower rates of heating primarily by contact with said combustion gases after their contact with 50 the second mentioned portion of the fluid conduit, the improvement which comprises commingling regulated quantities of steam with the combustion gases, after their use in the heating of the first-mentioned portion of the conduit and 55 prior to their contact with the second mentioned portion of the fluid conduit, whereby to reduce the convection component of the heat supplied thereto and whereby to increase the heat supplied from the combustion gases to the succeed- 60 ing portion of the fluid conduit.

2. In the heating of fluids in furnaces having fluid heating tubes subjected to relatively high rates of heating by radiation from combustion gases and hot refractory furnace walls, addition- 65 al fluid heating tubes subjected to excessively high rates of heating by radiation and by direct contact with said gases, and still other fluid heating tubes subjected to lower rates of heating primarily by contact with said gases after 70 their contact with the second-mentioned tubes; the improvement which comprises commingling regulated quantities of steam with the combustion gases after their use in the heating of the first-mentioned tubes and prior to their contact 75

with the second-mentioned tubes, whereby to reduce the convection component of the heat supplied to the second-mentioned tubes and whereby to increase the heat supplied from the 5 combustion gases to the third-mentioned tubes.

3. The improvement as defined in claim 2 fur-

ther characterized in that additional quantities of steam are commingled with the combustion gases after their contact with the second-mentioned tubes and prior to their contact with the third-mentioned tubes.

LEV A. MEKLER.
